UNITED STATES PATENT OFFICE.

JAMES M. OWEN, OF EMERSON, ARKANSAS.

POLISHING COMPOSITION.

No Drawing.

Application filed September 20, 1923. Serial No. 663,903.

To all whom it may concern:

Be it known that I, JAMES M. OWEN, a citizen of the United States, residing at Emerson, in the county of Columbia and 5 State of Arkansas, have invented certain new and useful Improvements in Polishing Composition; and I do hereby declare the following to be a full, clear, and exact description of the same.

10 This invention relates to a polishing composition particularly adapted for polishing automobile or other vehicle bodies, furniture, etc.

The composition consists of gasoline, varnish, turpentine and castor oil, preferably in the following proportions:

12 gallons of gasoline
4½ gallons of varnish
4 pints of turpentine
1 gallon of castor oil.

These ingredients are to be well mixed together into a homogeneous composition and may be applied by a brush, sponge or cloth, the surface being first washed.

What I claim is:

The herein described polishing composition consisting of twelve gallons of gasoline, four and one-half gallons of varnish, four pints of turpentine, and one gallon of castor oil.

JAMES M. OWEN.
